TOM FORREST, OF NORTH ANDOVER, MASSACHUSETTS, ASSIGNOR, BY DIRECT AND MESNE ASSIGNMENTS, TO DUPLEX YARN COMPANY, OF BOSTON, MASSACHUSETTS, A CORPORATION OF MASSACHUSETTS.

SPINNING AND DOUBLING MACHINE.

Application filed October 10, 1917. Serial No. 195,842.

To all whom it may concern:

Be it known that I, TOM FORREST, a citizen of the United States, and a resident of North Andover, county of Essex, and Commonwealth of Massachusetts, have invented an Improvement in Spinning and Doubling Machines, of which the following description, in connection with the accompanying drawings, is a specification, like characters 10 on the drawings representing like parts.

This invention relates to yarns or threads and has for one object the production of a novel mechanism for simultaneously spinning and doubling the yarn as one operation. 15 In this connection I use the term "spinning" with the usual meaning, as comprising the final drafting of the roving on the spinning frame and the imparting of the spinning twist to the individual strands.

20 My invention has also for its object the production of a mechanism that will, if desired permit simultaneous spinning of one roving composed of short fiber material and a second roving composed of relatively long fiber material. My improved machine will, after spinning the individual yarns, effect the folding or doubling thereof to produce a two-ply thread or yarn, having also the novel characteristics hereinafter mentioned.

25 Another object of this invention is to produce a machine that will make it possible to spin a given grade of material, as worsted, or other long fiber material, as distinguished from short fiber material, as cotton, into finer and smoother threads or yarns; and reduce very materially both the time necessary for and the cost of performing the above operations.

30 This application is, in part, a continuation 40 of my prior application, Serial No. 82,756.

The common practice, particularly in spinning worsteds is to pass the roving through the several sets of drafting or drawing rolls to reduce it to the desired size for the final 45 drawing through the rolls upon the usual spinning frame, from which it is led directly to the bobbin, the spinning twist being put into the single strand as it is wound on. The bobbins are then frequently removed to 50 a twisting machine where two or more strands are twisted together to form a multi-ply yarn.

During the passing of the roving, from the delivery set of drawing or drafting rolls on the spinning frame to the bobbin, the drafted roving, by the usual method, is subjected to quite a severe pull or drag which limits the degree of fineness to which a given grade of yarn can be spun, on account of the possibility of a single roving having too few 60 fibers or serrations to bear the strain or so-called drag when an unusually fine thread is desired.

Hence, in order to spin a finer thread or 65 yarn than is now possible from a given grade of wool, or other material, and particularly if of low grade fibers, and I use the words "threads and yarns" generically and interchangeably herein, I have conceived the idea of reducing the length of the spun yarn 70 subjected to the drag during the spinning of the same, and of bringing together and twisting, during the progress of the rovings from the drafting rolls to the single bobbin, of a plurality of spun threads or yarns, the 75 doubling twist of the multi-ply thread or yarn running in the same direction as the spinning twist of the individual yarns. By this method I practically blend the spinning operation into the doubling operation upon 80 the same machine, the twisting of the doubled multi-ply yarns being effected preferably between the pot eye or guide and the bobbin where the yarns undergo the greatest strain.

85 For the purpose of aiding a clear understanding of my invention, I have shown in the accompanying drawing so much as is necessary of a conventional form of worsted spinning machine, having incorporated therein the novel features of my invention for spinning and twisting a multi-ply yarn.

In the drawings:—

Fig. 1 is an end elevation, partly in section, of the roll stand of a spinning frame, 95 and a bobbin;

Fig. 2 is a plan of the same, parts being broken away, and

Fig. 3 is a detail of the pressure applying means for the drafting rolls.

Fig. 4, a plan view of a conventional form of traverse construction for controlling the planes of travel of the rovings through the drafting rolls and the planes of travel

of the rovings from the front drafting rolls to the guide;

Fig. 5, a front elevation of said parts;

Fig. 6, an end elevation from the right; 5 and

Fig. 7, a modification of the arrangement of drafting rolls hereafter to be described.

Referring to Figs. 1 and 2, the present embodiment of my invention comprises the 10 usual roll stand 1, herein supported on the beam 2, and having the usual thread guide or pot eye 3, in the thread guide board 4, carried by the bracket 5.

The roll stand carries at its forward end, 15 and suitably mounted therein, on one shaft 6, the lower, steel, fluted drafting rolls 7, 8. Above the same and supported by brackets 9 on the stand 1, on a single shaft 10, are upper, front drafting rolls 11, 12, which 20 may also be of metal and preferably leather covered, an upper and lower roll, constituting a pair, the two pairs comprising what I term for convenience, a set.

In order to obtain the required pressure 25 on the upper front rolls, I provide Fig. 1 the usual horn 13 which may be upwardly and forwardly extended from the front end of the roll stand or other convenient support.

30 This horn is notched or apertured to receive the lower upturned end of a hook 14, the upper end being received by a saddle 15 resting on and over the shaft 10. The hook 14 is threaded at its upper end and provided 35 with a wing nut 16 and a coil spring 17, by means of which a yielding pressure of desired degree is maintained on the rolls 11, 12.

Back of the lower front rolls, Figs. 1-2, 40 and at a suitable point on the roll stand 1, are positioned what may be called the lower forward carrying rolls or bosses 18, 19 of steel on a shaft 19 having reduced ends 20, and Fig. 2 upper forward carrying rolls 21, 22, of wood, having gudgeons 23-23 received in bearings 24, spaced from the rolls 18, 19, sufficiently to permit the rovings to be carried freely by them.

45 Adjacent these rolls, and mounted in similar but movable roll carriers or bearings 26, 27, are Figs. 1-2, what I term intermediate similar lower carrying rolls 28, 29, as of steel with reduced ends, 30 and Fig. 2, upper intermediate wooden rolls 31, 32 having gudgeons 33-33, spaced sufficiently from 50 the rolls 28, 29, to permit the rovings to be carried by them. The carriers 26, 27 for these rolls have each a depending arm 34 which extends through a slot 35 in the top of the roll stand 1, the lower arm ends being turned up to receive each, one end of a shaft 36 carrying on each end a pinion 37 in mesh with a rack 38 on the lower face of the stand 1.

60 The shaft 36, by means of a crank on one end, not shown, may be rotated to move the

carriers 26, 27 toward or from the forward carrying rolls 21, 22, as may be required for the particular work in hand.

Adjacent the carriers 26, 27 Fig. 2 and properly positioned with respect thereto is 70 one novel feature of my invention, viz, a set of intermediate combined carrying, pressure and drafting rolls, comprising an upper, short-fiber-drafting steel roll or boss 38^a, steel pressure roll 39, and wooden carrier roll 75 40 fast on the shaft 41, and lower cooperating short fiber steel drafting and pressure rolls 42, 43, respectively fluted, with reduced ends 44, all Fig. 1, in a carrier 45 similar to the carrier 27, with an arm 46 and pinion 80 47 on shaft 47^a, also in mesh with the rack 38. This carrier also has a pressure rod 49 threaded at its upper end to receive a wing nut 50 and spring 51 by means of which, and a saddle 52, the upper rolls 38, 39, are 85 given the proper pressure upon the rolls 42, 43.

The pressure roll 39 and drafting roll 38^a, 90 are of the same diameter and contact with the lower rolls 42, 43, while the carrying roll 95 40 is of less diameter and does not contact with roll 43.

Near the rear, or upper end of the roll stand is a second novel feature of my invention, the set of rear, combined long-fiber-drafting, pressure and carrying rolls, or 100 bosses, comprising the upper carrying roll 54, pressure roll 55 and drafting roll 56 on the same shaft 57, and below and on one shaft 58, the two fluted lower steel drafting and pressure rolls or bosses 59, 60. As in the case of the rolls 38^a, 39, 40, the pressure roll 55, and drafting roll 56, are of the same 105 diameter and contact with the rolls 59, 60, while the carrying roll 54 is of less diameter 110 and does not contact with roll 59. I have heretofore referred to the drafting rolls as being preferably made of steel for the reason that such is the practice at the present time, but obviously the material of which 115 they are made has no bearing upon my invention disclosed herein, and the rolls may be made of any suitable material that will perform the functions required of drafting rolls.

When drafting long staple material, Fig. 2, as long fiber wool, represented herein by the roving *a*, it is drafted from roll 56 to roll 12, the roll 40 being smaller in diameter that the roll 38^a, permitting the roving *a*, to 120 pass under it and upon the roll 43, the rolls 40, 43, acting as carriers. The shaft 41, however, is provided with the pressure roll 39 referred to, to engage the lower roll 43 and retain the rolls in proper position. If one 125 wishes to use with the roving *a* of long fiber material, a roving composed of short fiber material and to simultaneously draft a roving of short fiber material, as short fiber wool, however, the distance between 130

one pair of the front drafting rolls and their cooperating drafting rolls must be shortened, for instance, a short fiber drafting roll 38^a, already referred to may be used intermediate the rear carrying roll 54 and front drafting roll 11, the short fiber drafting roll thereby becoming, in effect, the rear drafting roll, and means provided for carrying the roving freely to the short fiber roll. 5 In the use of the words "long" and "short" with reference to the length of the fibers, it will be understood that they are merely relative terms and have no specific commercial significance. 10 To that end, Fig. 2, I have constructed roll 54, as stated, of smaller diameter than 15 56, permitting thereby the roving *b* of short fibers to pass freely between the upper roll 54 and lower roll 59 beneath it. The roll 20 38^a is of proper size to engage roll 42 and act as a drafting roll, and when the roving *b* of short fiber material reaches it the roving will be drafted between rolls 38^a and 11. 25

In Fig. 2, the line *b*, as stated, represents the roving of short stable fibers, running freely beneath roll 54 and being drafted from the roll 38 to 11; while the roving of long staple fibers is represented by the line *a*, which runs freely beneath roll 40 and is 30 drafted between rolls 56 and 12. In such case the rear drafting rolls 38^a and 56 would be of non-uniform distances from the front rolls. 35

The two rovings therefore may be spun in any desired manner with any desired 40 ratchet (or spacing of drafting rolls) and draft, by means of the rack and pinion adjustment. Of course, if it is desired to draft two rovings of fibers of equal length in the usual manner, the top rear carrying roll 54, pressure roll 55, and drafting roll 56, and top intermediate drafting roll 38^a, pressure roll 39, and carrier 40 are removed. Upper drafting rolls 56^a, Fig. 7, similar to 56, 45 are substituted for rolls 54, 55, 56, and conventional carrying rolls 31^a, 32^a, similar to 31, 32, may be substituted for rolls 38^a, 39 and 40. The back drafting rolls and carrying rolls, as required, are then spaced from 50 the front drafting rolls according to the length of fibers to be spun. 55

In the foregoing description I have referred, for convenience, to the separate bosses on the same shaft as separate rolls, even when they are fixed on the shaft. 60

Referring to Figs. 1 and 2, the rovings *a* and *b* are shown as being fed from the forward or delivery set of these rolls 7, 8, to a single guide 3, or obviously two guides side by side might be used intermediate the vertical planes of the roving *a*, *b*, on the rolls 7, 8, from which they are carried to and wound on the bobbin 61. 65

To form a multi-ply yarn with the characteristics hereafter described, the yarns *a*, 70

b, are doubled at or near the guide 3. Obviously, by bringing together and twisting the yarns *a*, *b*, at the guide 3, the strain usually imposed on each yarn by the ordinary method of spinning between the guide 3 and the bobbin 61, is borne by a multi-ply yarn, and the strain on the individual yarns being thus reduced, each may be individually spun finer, with a resulting finer product when twisted with the other yarn. This 75 novel construction therefore permits the spinning of a finer yarn from a given fiber than is now possible. The spinning frame may be provided with any suitable device for determining the planes of the line of 80 travel of the rovings between the rolls and the angularity of the planes of travel of the rovings from the front drafting rolls to the guide, such as a traverse, and in Figs. 4, 5 and 6, I have illustrated one conventional 85 form of such construction.

The lower rear roll 60, Figs. 4, 5, is provided near its longitudinal center with a worm 61 in mesh with a worm gear 61^a on the shaft 63 on the ribbed support 64 of the 90 frame 1. The rear end of the shaft 63, Fig. 4, carries a cam 65 which rotates between and in contact with two rolls 66, mounted in brackets 67 on the traverse 62. Upwardly extended from the traverse 62 are the yarn 95 guides 68. It will be obvious that, as the roll 60 rotates, it will, through the connections described, cause rotation of the cam 65 and this, in turn, will impart reciprocating motion to the traverse 62 by means of 100 the rolls 66.

As the rocking of the traverse 62 shifts the rovings *a*, *b*, back and forth in the usual manner longitudinally of rolls 54, 56 and changes the angularity of the feeding of the 105 rovings, it will be evident that this shifting results in making each yarn *a*, *b*, between the rolls 11, 12, and the guide alternately the long and short one of the two, as it is spun, according to the position of the traverse and the yarns between the drafting rolls and the guide 3. As shown, Fig. 2, the yarn *a*, is the short yarn of the two, and the yarn *b*, is the long one. 110

Obviously the traverse action can, if desired, be modified by properly controlling the action of the same, or even suspended temporarily, as by removing one of the rolls 66 from contact with the cam 65 or by adjusting its position relative thereto so that the harder spun end of a section of one yarn will be folded with the harder spun end of a section of another yarn in the completed or multi-ply yarn; or so that the sections may be omitted or spaced farther apart in either 120 or all the strands making up the completed 125 yarn. In any such case the product, while not as satisfactory, would still be within the scope of my invention.

It will be clear that the short yarn *a* as 130

shown in Fig. 2, will be twisted to a greater extent between the roll 12, and the guide 3, than the long yarn *b*, if the fibers composing the two yarns are of substantially the same length, and, when shifted, and the yarn *b* becomes the short one, it will, in turn, be twisted to a greater extent while it is the short yarn than the yarn *a*, at that time the long one; this greater or harder twist being 10 a progressive condition varying in degree as each yarn gradually becomes first the long and then the short one of the two:

This shifting or changing of the angularity of the feeding of the rovings and 15 yarns simultaneously with the spinning action, obviously produces in the individual yarns, as they are spun, alternate lengths or sections of what are oppositely, progressively, hard and soft twisted material; that 20 is, the section of a given yarn while it is the shorter one of the two, will be twisted harder at first and then progressively softer as it becomes first of equal length with, and then longer than its mate, while the following section 25 of the same yarn will be twisted progressively softer while it is the longer of the two yarns and progressively harder during the time that it is gradually becoming the shorter of the two yarns.

30 It will also be evident, that the bringing together at or near the guide 3 of the two oppositely, progressively, hard and soft twisted yarns, will result in the hard twisted end of one section of one yarn being folded 35 with the soft twisted end of the corresponding section of the other yarn; while the soft twisted end of one section of the first yarn will also be folded and twisted with the hard twisted end of the corresponding section of 40 the other yarn, producing a two-ply yarn *c* of substantially uniform size, and relatively finer than any two-ply yarn that can now be produced by the common methods of and machines for spinning. I am therefore 45 able, by my novel method and machine for spinning to spin a plurality of rovings into substantially complete threads or yarns, and then twist or double the individual rovings previously spun and twisted, both the spinning 50 twist and the twisting twist being effected in the same direction, and producing a multi-ply yarn or thread as soft as a thread or yarn now produced by the common methods and machines.

55 If yarns of substantially unequal length of fibers are used, the yarn having the longer fibers naturally takes more twist than its mate. It therefore follows that although under the influence of the traverse, each 60 yarn will have alternately progressive sections of hard and soft spun yarn, and will be folded with the opposite yarn so that the folded sections have opposite progressions, yet with yarns of substantially unequal fibers 65 the point of extreme softness of twist in a

section of one yarn may be harder than the point of extreme hardness in the opposite yarn.

In producing a yarn having the characteristics pointed out above, namely, alternate sections of progressively hard and soft twisted yarn, the guide 3 is an important element. Obviously, in order to obtain the full effect in each yarn of the traverse action that is, the controlling of the angularity of the planes 75 along which the yarns are fed to the guide 3, it is necessary that the two yarns be restrained in some manner so that they cannot follow freely the traverse action back and forth. 80

In other words, the multi-ply yarn must be substantially held at or about the doubling point of the two yarns, against travel, in order that the undoubled or free portions 25 of the individual yarns may partake of the traverse action or their planes of travel controlled and thereby each alternately become the longer and the shorter of the two.

To attain this object, I make use of the guides 3 to receive a plurality of rovings, 90 positioned between and preferably substantially midway between the two drafting rolls, approximately three inches apart, and between the planes of travel of the two rovings between the rolls. The guide being 95 fixed between these planes of travel, it prevents the doubled yarn from moving laterally with the traverse to any appreciable extent, and thereby ensures the individual, undoubled yarns partaking of the motion 100 of the traverse to produce the result desired. Obviously, if the doubled yarns were not restrained as by the guide 3, they, too, would partake of the motion of the traverse to such an extent that each of the undoubled 105 yarns would be always substantially of the same length between the doubling point and the drafting rolls, and no progressive twisting action would be effected.

It is, moreover, desirable for the strength 110 of the yarns that each be spun until it is substantially a completed yarn before it is doubled with the other yarn or yarns. To accomplish this object, that is, control the angularity of the planes of travel of the rovings after they leave the drafting rolls, the doubling point of the yarns must be retained 115 at a sufficient distance from the drafting rolls to permit the necessary separate twisting of the individual yarns, as already stated. Obviously, the nearer the doubling point of the two arms of the fork of yarn approaches the bight line of the drafting rolls, the greater the amount of twist that is imparted to each yarn or each arm of the 120 fork.

In this case also, the angularity of the planes of travel of the rovings to the guide is partly controlled by the traverse action.

Accordingly, it will be noted that the 130

yarns are doubled at or about the guide 3, and to permit each roving to be separately spun its angularity of feed or travel is controlled and the two rovings are separated on the drafting rolls, as stated, substantially three inches, which permits each yarn to be separately spun to the desired degree before it is doubled with the opposite yarn. It will be clear that this separate spinning of each yarn could not be effected if the rovings were fed between the drafting rolls very near each other as, particularly if wool, they would run together during the spinning action and would be doubled much nearer the drafting rolls than is the case according to my improved method.

The usual twisted multi-ply thread or yarn, made according to the common practice, must be twisted, when folded, in the opposite direction to the spinning twist, to keep it soft and pliable, because if twisted in the same direction as the individual threads were spun, (with the large amount of twist necessary to sustain the thread when traveling the distance to and being wound on the bobbin as a single thread) it would be hard to handle, and unsuitable for ordinary warp use; but the thread produced by my improved process, as stated, is soft and pliable although twisted in the same direction each time, and may be used in any case where such yarn is desired because of the lesser strain naturally imposed on the short length of single yarn which allows for a less amount of twist.

Another important advantage results from the use of my improved machine, and that is the production of a smoother thread. In spinning, the loose fibers of that part of each roving that is free, i. e., between the rolls 11, 12, and the bobbin, tend to fly outwardly, forming a thread with a rough surface or beard. Obviously the fibers will be thrown out to a much greater extent under the usual method of spinning where the single roving is carried from the feed rolls 11, 12, to the spindle, owing to the greater distance between the two, than in the case where the single rovings are doubled at or near the guide, thereby shortening the length of the free threads from which the fibers may be thrown out, to the distance between the rolls 11, 12, and the guide 3.

After reaching the guide, the several yarns being twisted about each other, each acts to prevent the throwing out of the loose fibers or beard from the other, as now happens, and the result is that the yarns brought together and twisted by my improved machine, have a very much smoother surface than yarns first spun and then again twisted in the opposite direction by the present method and spinning and doubling machines. The fact that by my novel machine the spinning-twist and the twisting-twist are effected

in the same direction, facilitates this result, because, as now practiced, the spinning-twist in the thread is taken out to some extent by the effecting of the twisting-twist in the opposite direction, thus permitting the fibers to be loosened and thrown out somewhat during the second twisting or doubling.

By my improved machine the step of doubling and twisting, as a separate step in the production of multi-ply threads is entirely eliminated, because such operation is effected simultaneously as one operation with the initial spinning. It will be evident that my improved machine results in a very large reduction in the cost of the so-called spinning operation, owing to the fact that the number of spindles is cut down 50%, together with all the parts necessary for the operation of the same, including the tension tape band, etc., tin separators are not needed, and the labor, including doffing, is reduced by 50%. The number of delivery rollers is not reduced, nor is their output. On the contrary, the speed of the spindles may be reduced, saving wear and tear, and the speed of the delivery rollers increased because the output of the latter may be increased with the decrease in speed of the spindles, and the degree of twisting effected.

Furthermore, after spinning and twisting the thread by the common machines, it is subsequently wound from one or more bobbins on to a large spool or container known as a package, which is too large to be used economically on a spinning frame, because its use would necessitate placing the spools so far apart as to reduce materially the number of them that could be used in a given floor space.

By my improved spinning and twisting machine, more room is naturally provided on the machine for each bobbin, thus leaving room for the use of an enlarged bobbin or package on which the spun and twisted yarn can be initially wound, thus materially reducing the cost of subsequent winding operations.

By means of my improved spinning and doubling machine I am able also to practice economy in the formation of a multi-ply yarn by the use of both long and short fiber material where such a combination is desirable. In fact, the multi-ply yarn comprising both long and short fiber material that is spun and doubled on my novel machine, is a stronger and smoother yarn than the yarn made by separately spinning and then doubling the yarns in the common manner because the former yarn contains the peculiar characteristics of the yarn spun and doubled on my machine, already pointed out and described. However, obviously the novel construction herein described for drafting rovings of different length fibers may be availed of whether or not the rovings are subsequent-

ly spun and doubled as described herein or in the common manner.

While machines have been devised which attempt to simultaneously impart a spinning twist to individual threads and subsequently a twisting thereto in the opposite direction, I do not know of any machine for simultaneously spinning, doubling or bringing together a plurality of yarns, and twisting them again in the same direction, and winding them on a container, all as one operation.

My invention is not limited to the particular embodiment thereof illustrated and described, but its scope is rather determined by the claims.

Claims:

1. A spinning and doubling machine comprising two or more pairs of drafting rolls, a traverse and a bobbin between two vertical planes across the axes of any two pairs of rolls.

2. A machine for simultaneously spinning a plurality of yarns separately to substantial completion and twisting them together in the same direction as the spinning twist comprising front drafting rolls, cooperating drafting rolls at non-uniform distances from the front rolls, a guide between the planes of travel of the rovings on the rolls and substantially at the meeting point of the rovings to fix the angularity of the planes of travel of the yarns, a traverse to move the rovings laterally on the rolls to cause each roving to become alternately longer and shorter than its mate between the guide and the front rolls.

3. A machine for producing a separable, multi-ply yarn, each ply having progressively hard and soft spun sections therein, comprising drafting rolls, a guide within the planes of travel of the rovings on the rolls, and a traverse to determine the angularity of the planes of travel of the rovings and cause each to become alternately the longer and shorter of the two, relative to the guide.

4. A spinning and doubling machine comprising front drafting rolls and cooperating drafting rolls at non-uniform distances from the front rolls, means to control the angularity of the planes of travel of the rovings, and a bobbin, for simultaneously spinning and doubling rovings of different length fibers.

5. A spinning and doubling machine comprising front drafting rolls, a set of cooperating intermediate drafting, pressure and carrying rolls, the lower rolls of this set being of the same diameter, and a set of rear combined drafting, pressure and carrying rolls, the lower rolls being of the same diameter, the drafting and carrying rolls being of different diameters.

6. A spinning and doubling machine comprising front drafting rolls, a set of cooperating intermediate drafting, pressure and

carrying rolls, the lower rolls of this set being of the same diameter, and a set of rear combined drafting, pressure and carrying rolls, the lower rolls being of the same diameter, the drafting and carrying rolls being of different diameters, and a common guide for all the drafting rolls.

7. A spinning and doubling machine comprising means for drafting a roving of long fibers and separate means for drafting simultaneously a roving of relatively shorter fibers, a common guide therefor, and a common spindle for imparting the spinning twist and the doubling twist to the yarn in the same direction, and means for feeding a plurality of rovings simultaneously and at different angles to the guide.

8. A spinning and doubling machine comprising front drafting rolls, a set of intermediate rolls comprising a pair of drafting rolls and a pair of combined pressure and carrying rolls, and a set of rear rolls comprising a pair of drafting rolls and a pair of combined pressure and carrying rolls, a pot-eye between the front drafting rolls, and a bobbin, whereby a roving of fibers of given length may be drafted between the front drafting rolls and the intermediate drafting rolls and a roving of fibers of different length may be drafted between the front drafting rolls and the rear drafting rolls, and the two rovings simultaneously spun and doubled.

9. A spinning and doubling machine comprising a set of drafting rolls, an additional pair of drafting rolls cooperating with one pair of said set, and an additional pair of drafting rolls cooperating with a second pair of the said set, the two last named additional pairs being at non-uniform distances from the said set.

10. Spinning and doubling mechanism comprising in combination a plurality of pairs of drafting rolls, adjustable in pairs to draft simultaneously rovings of different length fibers, and a guide between the paths of travel of the rovings.

11. A spinning and doubling machine comprising a plurality of pairs of drafting rolls, each pair comprising an upper and a lower roll, a plurality of pairs of drafting rolls in the rear of the former pairs and in operative alignment therewith, and means for positioning the rear pairs at relatively different distances respectively from and in independently operative relation to the cooperating front pairs.

12. Spinning and doubling mechanism comprising a traverse and a plurality of pairs of drafting rolls at non-uniform distances from each other and so positioned as to distance one from another as to permit simultaneous drafting of rovings of different length fibers.

13. A spinning and doubling machine comprising a plurality of pairs of draft-

- ing rolls in substantially axial alignment, a pot-eye in a plane between the adjacent ends of two pairs, and a traverse for changing the angularity of feed of the rovings whereby 5 a plurality of rovings may be simultaneously spun and twisted to effect first progressively hard and subsequently progressively soft sections therein.
14. A spinning and doubling machine 10 comprising a set of drafting rolls, a pot-eye located in a plane between adjacent ends of said rolls, and a traverse whereby the rovings may be moved simultaneously laterally relative to the pot-eye to cause each roving 15 to become alternately longer and shorter than its mate and thereby produce in each roving a succession of progressively hard and soft spun sections, and the rovings subsequently folded and twisted together in 20 the same direction as the spinning twist.
15. A spinning and doubling machine 25 comprising a set of drafting rolls, a guide in a plane between the adjacent ends of said rolls, and a traverse for feeding the rovings to a common guide while imparting a spinning twist thereto in a regularly progressive and alternately increasing and diminishing degree and doubling the spun rovings in the same direction as the spinning twist.
16. A spinning and doubling machine 30 comprising a set of drafting rolls, a single pot-eye in a plane between the adjacent ends of said rolls, and a traverse for feeding a plurality of rovings directly and separately to and along planes of travel at unequal distances from the single pot-eye and simultaneously spinning each roving to a substantially complete thread as it is fed toward the pot-eye, subsequently folding the rovings near the pot-eye and tying down the free fibres of one roving while spinning the other roving about them.
17. In spinning and doubling mechanism, 35 the front drafting rolls 7, 11, 8, 12, a pair of intermediate drafting rolls 38, 42, cooperating with one pair of the front rolls, intermediate combined pressure and carrying rolls 39, 40, 43; rear drafting rolls 56, 40 60, cooperating with a second pair of the front rolls, and combined pressure and carrying rolls 54, 55, 59, at a greater distance from the front drafting rolls 7, 11, 8, 12, the guide 3, succeeding said rolls and 45 the traverse 62 to feed a plurality of rovings along first parallel, and then angularly changing planes to the drafting rolls and the guide 3.
18. Spinning and doubling mechanism 50 comprising the front drafting rolls 7, 11, 8, 12, rear drafting rolls cooperating therewith, intermediate drafting rolls also cooperating therewith, the guide 3 succeeding said rolls, the roving traverse 62 to 55 feed the rovings intermittently along dif-
- ferent paths and determine the angularity of the planes of travel of the rovings to the guide, whereby rovings of different length fibers may be simultaneously spun and doubled.
19. Spinning and doubling mechanism 60 comprising a plurality of pairs of drafting rolls adjustable in pairs to draft simultaneously rovings of different length fibers, a guide so positioned respecting the drafting rolls as to determine the angularity of feed of the rovings and effect the simultaneous imparting of the spinning and doubling twist to the rovings.
20. A spinning and doubling machine 65 comprising means for drafting a roving of long fibers, means for drafting simultaneously a roving of relatively shorter fibers, a common guide, and means for controlling the angularity of the planes of travel of the rovings to the guide, and a common spindle for simultaneously spinning and doubling rovings of different length fibers.
21. A spinning and doubling machine 70 comprising means for drafting a roving of long fibers, means for drafting simultaneously a roving of relatively shorter fibers, a common guide, and means in front of the drafting rolls for controlling the angularity of the planes of travel of the rovings to the guide, and a common spindle for simultaneously spinning and doubling rovings of different length fibers.
22. A spinning and doubling machine 75 comprising means for drafting a roving of long fibers, means for drafting simultaneously a roving of relatively shorter fibers, a common guide, and means in the rear of the drafting rolls for controlling the angularity of the planes of travel of the rovings to the guide, and a common spindle for simultaneously spinning and doubling rovings of different length fibers.
23. In a spinning and doubling machine, 80 a shaft having a plurality of complete rolls or bosses thereon, the diameters being of different measurement to permit the passage of certain rovings past the rolls or bosses of lesser measurement.
24. A spinning and doubling machine 85 comprising one or more sets of drafting rolls, the pairs of the respective sets being at non-uniform distances from each other, a roving traverse, and a guide between two vertical planes across the axis of one of said sets of rolls.
25. A spinning and doubling machine 90 comprising two end-wise abutting pairs of drafting rolls, a guide in a plane between the outer ends of the pairs, and a traverse to feed the rovings along changing paths to the guide.
26. A spinning and doubling machine 95 comprising a plurality of pairs of front drafting rolls, a common guide therefor,

and a traverse arranged to feed the rovings to the guide at simultaneously changing angles.

27. A spinning and doubling machine comprising means for drafting a roving of long fibers, means for drafting simultaneously a roving of relatively shorter fibers, and a common guide for both of said drafted rovings.

10 28. A spinning and doubling machine comprising means for drafting a roving of long fibers, means for drafting simultane-

ously a roving of relatively shorter fibers, and a common bobbin to receive both of said drafted rovings.

15

29. A spinning and doubling machine comprising means for drafting a roving of long fibers, means for drafting simultaneously a roving of relatively shorter fibers, and a common guide and bobbin for the said drafted rovings.

In testimony whereof, I have signed my name to this specification.

TOM FORREST.
